UNITED STATES PATENT OFFICE.

FRANK BILLINGS, OF CLEVELAND, OHIO.

LOADING-MACHINE.

1,265,729.

Specification of Letters Patent. Patented May 14, 1918.

Application filed January 12, 1911. Serial No. 602,176.

To all whom it may concern:

Be it known that I, FRANK BILLINGS, a citizen of the United States, residing at Cleveland, in the county of Cuyahoga and State of Ohio, have invented a certain new and useful Improvement in Loading-Machines, of which the following is a full, clear, and exact description:

The object of this invention is to provide 10 a machine adapted for use in mines, by means of which the coal or mineral which is broken from the working face or breast in the mine may be gotten out of the way, and loaded into the mine cars quickly and 15 economically.

The invention consists in the novel combinations of parts, shown in the drawing, and hereinafter described and defined by 20 the appended claims, which contribute to the efficiency and practical value of said machine.

In the drawing, Figure 1 is a plan view and Fig. 2 a side elevation of the machine embodying the invention. Fig. 3 is a longitudinal vertical sectional view of a part of the rocker to be hereinafter described and the parts supported thereby. Fig. 4 is a plan view of the wheel truck forming a part of the machine. Fig. 5 is a transverse vertical sectional view through the rocker and parts carried thereby in the plane indicated by line 5—5 on Fig. 2. Fig. 6 is a transverse vertical sectional view on line 6—6 of Fig. 2.

35 The machine includes a wheel truck A, the wheels a and a' of which are adapted to run on the mine tracks; and a superstructure supported on said truck and adapted to be moved thereon in a horizontal plane about a 40 vertical axis, said superstructure carrying numerous working parts to be presently explained.

The truck frame is a built-up structure comprising side members a^2 and transverse members a^3 . Fixed to this truck are two segmental tracks a^4 , a^5 , whose center of curvature is the axis about which the superstructure will swing. The ends of these tracks may be connected by side bars a^6 .

45 The base of the superstructure is a built-up rectangular frame which includes, in

the form shown, the side member b , the cross members b' and supplemental longitudinal members b^2 . It is to be understood, however, that the particular construction of this base frame is not at all material to the invention. 55

There are also two transversely extended beams C, C', which are rigidly fastened to and are located below the superstructure 60 base above described. Flanged wheels c , c' are mounted on these bars C, C', and they ride on the rails a^4 , a^5 . A reversing electric motor F which is mounted on the truck frame is connected by a suitable train of reducing gearing with a shaft D to which a 65 conical pinion d is fixed. This pinion engages with a segmental rack b^5 fixed to the superstructure base frame. As the motor, through suitable reducing gearing, rotates 70 the pinion d in one direction or the other, the superstructure frame will be swung laterally in one direction or the other in a horizontal plane, and will be guided by the engagement of the flanged wheels c' with the 75 tracks a^4 , a^5 , so that it will swing about an axis which is coincident with the axis of the two tracks a^4 , a^5 , this axis being, of course, to the rear of the truck frame and being preferably near the rear end of the 80 hereinafter mentioned conveyer.

This same motor may also be connected through a suitable train of gearing with the driving axle a^7 of the truck, whereby the truck may be caused to traverse the mine 85 tracks, and suitable clutch mechanism may be provided for connecting either train of mechanism with the motor.

Secured upon the base frame of the superstructure are two standards E which 90 furnish the bearing for a transverse shaft G. This shaft, in addition to its other duties, supports the rocker H. Two sleeves h of this rocker embrace the shaft G and lie respectively just inside of the two standards E. This rocker is rocked or tilted upon its supporting shaft so as to assume any desired angle to the horizontal by power derived from an electric motor J which is supported on the superstructure base. This 95 motor, through suitable reducing gearing, drives a crank shaft K mounted in the su- 100

superstructure frame. This shaft has two crank arms h fixed to it and to each of these cranks a link h' is pivoted, the upper end of both links being pivotally connected with a laterally extended bar z' fixed to the rocker H .

The rocker in the form shown is built up of suitable angle irons and plates and has a top and two vertical sides. The rocker 10 supports and guides the extensible hoe shank and certain counterbalances, to be presently explained. The hoe shank referred to comprises an outer tubular member M and an inner member N , which telescopes into the 15 outer member, and has the hoe blade N' fixed to its outer end. The outer member, is, for convenience, built up of channel irons m , a top plate m' and a bottom plate m^2 . It is supported and guided by and permitted to 20 move longitudinally between rollers h^3 , h^4 , the former being mounted on the rocker, and the latter being loose on shaft G . It has a rack m^3 on the bottom face of the bottom plate m^2 and this rack is engaged by a 25 pinion p fixed to a shaft P . This shaft is mounted in bearings fixed to the rocker. It has a gear p' at one end, and this engages with a pinion g' fixed to the shaft G . This shaft has at its other end a beveled 30 gear g^2 which meshes with a beveled pinion q fixed to the shaft of a reversing electric motor Q which is mounted on the superstructure base frame. The inner hoe shank N at its forward end rides between and is 35 supported and guided by rollers m^5 mounted on the hoe shank member M . Horizontal guide groove are formed on the outer faces of the two side members of this inner hoe shank near the rear end thereof, and these 40 grooves embrace longitudinally extended ribs m^6 , fixed to the inner face of the side members of the hoe shank member M . On the top of the member N is a rack n^4 and this is engaged by a pinion m^7 which is 45 mounted in bearings fixed to the top of the hoe shank member M . On the lower face of the top member of the rocker H is a rack h^8 also engaged by the pinion m^7 .

It is evident from the foregoing that 50 when the motor Q is operated in one direction it will, through the described mechanism, turn the pinion q , and thereby move the outer hoe shank member M outward or to the left, as shown in Figs. 2 and 3. The 55 pinion m^7 will, of course, go with the member M , and will be rotated by reason of its engagement with the fixed rack h^8 . Therefore, the inner hoe shank member N will be caused to travel outward or to the left, but 60 at a rate twice as great as the rate at which the member M travels. In other words, this inner member N will move out of the outer member M as the latter moves to the left in its supports upon the rocker. If, while this

is being done, or at any suitable time, the 65 rocker is tilted so as to carry its front end downward the hoe shanks will assume the angular position indicated by dotted lines in Fig. 2. If, now, the motor Q be reversed the telescoping hoe shanks M and N will 70 reverse their movement, and thereby the broken off mineral on the floor of the mine will be drawn toward the front end of the machine and up onto an apron S on the front end thereof, and thence onto a belt 75 conveyer V of any suitable construction mounted in the base frame of the superstructure. This conveyer, as shown, is of the endless belt variety. It is of familiar form, and therefore it is thought requires 80 no special description. The driving shaft W , therefore, is mounted on the base frame of the superstructure at the rear end thereof, and is driven by an electric motor Y mounted on said superstructure base frame 85 and connected therewith through a suitable train of reducing gearing.

The rocker H also carries in addition to the extensible hoe shank two counterbalances T which move simultaneously with, but in 90 a direction opposite to the hoe shanks. There are two of these counterbalances shown, one located just inside of each side member of the rocker and partly supported thereby. This is to say, the rocker has secured to each of its vertical side members two flanged track bars h^9 . A roller t fixed to the associated counterweighted bar T is supported and guided by these track bars. Each counterweight has a rack t' fixed to its 100 underface, and this engages with a pinion w mounted on a stub shaft which is fixed to the rocker, and the pinion W meshes with a pinion P^2 fixed to the shaft P .

Having described my invention, I claim: 105

1. In loading machinery, the combination of a rocker adapted to tilt upon a horizontal axis, and mechanism for tilting it, with a hoe having an extensible shank comprising an outer tubular member which is movably supported on said rocker and an inner member which telescopes into the outer member, a rack fixed to the outer member, a pinion supported by the rocker and engaging said rack, means for turning the pinion, a rack 115 upon said inner shank member, a rack upon the rocker, and a pinion mounted in bearings on the outer hoe shank and engaging with the two last mentioned racks.

2. In loading machinery the combination 120 of a rocker adapted to tilt upon a horizontal axis, a hoe shank movably supported by said rocker, means for moving said hoe shank, a counterbalance having a roller mounted at its rear end, grooved track irons 125 fixed to the rocker for engagement by said roller, a pinion rotatably mounted upon the rocker, a rack fixed to the counterbalance

engaging with said pinion, and means for driving said pinion.

3. In loading machinery, the combination of a wheel truck, a superstructure frame 5 mounted thereon to move in a horizontal plane, an inclined apron fixed to the front end of said frame, a conveyer mounted on said frame and extending from the front to the rear end thereof and projecting at its 10 front end beneath said apron, a rocker mounted on said frame and adapted to tilt on a horizontal axis, a hoe having a shank which is movably supported on said rocker, three independent motors, and mechanisms 15 through which said motors may respectively swing the frame, tilt the rocker and operate the hoe.

4. In loading machinery, the combination of a base frame, two standards fixed thereto, 20 a shaft rotatably mounted in said standards, a rocker pivotally supported upon said shaft, means for tilting the rocker, a motor supported on the base frame, intermediate mechanism for transmitting motion from said 25 motor to said shaft, a hoe shank comprising two telescoping members of which the outer member is tubular and is movably supported upon the rocker and has a rack on its lower face, and the inner member is movably supported upon the outer member and has a 30 rack on its top surface, a shaft mounted on said rocker carrying a pinion which engages the rack on the outer hoe shank, gearing transmitting motion to this shaft from the 35 shaft first mentioned, a rack fixed to the top of the inner hoe shank, a rack fixed to the rocker, and a pinion mounted in bearings fixed to the outer hoe shank, which pinion engages both of the last mentioned racks.

40 5. In loading machinery, the combination of a base frame, two standards fixed thereto, a shaft rotatably mounted in said standards, a rocker pivotally supported upon said shaft, means for tilting the rocker, a motor supported on the base frame, intermediate mechanism for transmitting motion from said motor to said shaft, a hoe shank comprising two telescoping members of which the outer member is tubular and is movably supported upon the rocker and has a rack on its lower face, and the inner member is movably supported upon the outer member and has a rack on its top surface, a shaft mounted on said rocker carrying a 45 pinion which engages the rack on the outer hoe shank, gearing transmitting motion to this shaft from the shaft first mentioned, a rack fixed to the top of the inner hoe shank, a rack fixed to the rocker, and a pinion mounted in bearings fixed to the outer hoe shank, which pinion engages both of the last mentioned racks, a counterbalance movably supported by said rocker and carrying a 50 rack, a pinion mounted on the rocker and

engaging said rack and also engaging a 65 pinion fixed to the pinion-carrying shaft before mentioned.

6. In loading machinery, the combination of a wheel truck provided with two segmental tracks having a common center, a superstructure frame carrying flanged wheels which ride upon and engage said tracks, a segmental rack carried by said superstructure frame, a pinion engaging said rack and mounted on the truck frame, mechanism 70 mounted on said truck frame for turning said pinion, a rocker mounted on the superstructure frame and adapted to tilt upon a horizontal axis, mechanism for tilting it, a hoe movably mounted upon said rocker, and means for moving the same backward and forward, a counterbalance supported on said rocker, and mechanism for moving said counterbalance in a reverse direction to but simultaneously with the hoe shank. 80

7. In loading machinery, the combination of a supporting member for a working tool; a reciprocating tool shank or holder movably supported by said member, said shank being composed of relatively movable parts; 90 mechanism connected to one of said parts for moving said part inwardly and outwardly; and means comprising rack and pinion gearing by which the second part is moved by the first part and at a relatively 95 different speed.

8. In loading machinery, the combination of a supporting member for a working tool, a reciprocating tool shank composed of relatively movable telescopic parts, mechanism 100 operatively connected with one of said parts for shifting the same inwardly and outwardly, and gearing for causing said part of the shank to transmit movement to the second part of the shank, said gearing including a rack carried by the supporting member. 105

9. In loading machinery, the combination of a supporting member for a working tool, a reciprocating tool shank composed of relatively movable telescopic parts, mechanism operatively connected with one of said parts to shift the same inwardly and outwardly, gearing by which a second part of the shank is moved by said first named part at a relatively different speed, said gearing including a rack carried by the supporting member, a rack carried by the second named part of the shank, and means carried by said first named part and engaging both of said 115 racks.

10. In a loading machine, a truck frame; a superstructure mounted thereon to move about a vertical axis; a conveyer carried by the superstructure and extending substantially from the front to the rear thereof, the vertical axis of movement of the superstructure being at the rear of the truck frame and 125

near the rear end of the conveyer; a rocker mounted on said superstructure to turn about a horizontal axis; a tool for bringing material up to the conveyer; a shank carrying said tool and supported by said rocker for inward and outward movement; and means, for rocking the rocker and reciprocating the shank.

In testimony whereof, I hereunto affix my signature in the presence of two witnesses.

FRANK BILLINGS.
